UNITED STATES PATENT OFFICE

FRANCES W. PIKE, OF CHICAGO, ILLINOIS, ASSIGNOR TO GENERAL ELECTRIC COMPANY, A CORPORATION OF NEW YORK

DESIGN FOR A CLOCK CASE

Application filed January 31, 1933. Serial No. 47,065. Term of patent 14 years.

To all whom it may concern:

Be it known that I, FRANCES W. PIKE, a citizen of the United States, residing at Chicago, county of Cook, State of Illinois, have invented a new, original, and ornamental Design for a Clock Case, of which the following is a specification, reference being had to the accompanying drawing, forming a part thereof. The figure is a front perspective view of a clock case showing my new design.

I claim:

The ornamental design for a clock case as shown.

In witness whereof, I have hereunto set my hand this 23 day of January, 1933.

FRANCES W. PIKE.
